UNITED STATES PATENT OFFICE.

LEWIS E. FAGAN, OF CHICAGO, ILLINOIS, ASSIGNOR TO EMIL BLUMENTHAL, OF EVANSTON, ILLINOIS, L. E. FAGAN, OF CHICAGO, ILLINOIS, AND E. G. TROWBRIDGE, OF WINNETKA, ILLINOIS, AS TRUSTEES FOR B. F. T. COMPANY, OF CHICAGO, ILLINOIS, AN UNINCORPORATED ASSOCIATION.

RAISING AND LOWERING DEVICE FOR DEMOUNTABLE WHEELS.

Application filed October 29, 1923. Serial No. 671,513.

To all whom it may concern:

Be it known that I, LEWIS E. FAGAN, a citizen of the United States, and a resident of Chicago, Cook County, and State of Illinois, have invented certain new and useful Improvements in Raising and Lowering Devices for Demountable Wheels, of which the following is declared to be a full, clear, and exact description.

10 This invention relates to raising and lowering devices for demountable wheels, and its principal object is to provide a device for use in mounting vehicle wheels upon the spare wheel carrier of motor vehicles, and 15 for demounting them and placing them upon the ground, which device shall be of simple and practical construction, and which shall be comparatively inexpensive, and highly efficient for the purpose intended.

20 It is common practice to provide motor vehicles, such as automobiles, trucks, and the like, with a carrying device for carrying a spare wheel, which may be taken off the carrier and substituted for one of the 25 wheels that are in use, in case of an emergency. It is also well known that metal vehicle wheels are heavy and cumbersome, and that the task of demounting the spare wheel from its carrier and lowering it to the 30 ground is awkward and laborious, as well as, the task of raising and attaching the wheel to the spare wheel carrier.

One of the objects of this invention is to provide a raising and lowering device embodying two connectible and disconnectible members of a lever, capable of engaging in a hole as for instance one of the usual bolt holes of metal wheels, in such manner that one part of the lever is behind the wheel 35 and the handle part thereof is in front of the wheel, whereby the user may conveniently take hold of the handle portion of the lever in manipulating the same to raise the wheel to the carrier and to lower it therefrom.

Another object is to provide a wheel raising and lowering device which may be applied at the rear or at the sides of automobiles. Another object is to provide a wheel 50 raising and lowering device for use in connection with wheels that are carried on the sides of automobiles having pockets in the

running boards or fenders. Another object is to provide a wheel raising and lowering device capable of use in connection with 55 a spare wheel carrier of the type which employs threaded studs for securing the wheel to the carrier. Another object is to provide a carrier plate of simple, strong and substantial construction formed from a single 60 piece of sheet metal, upon which the raising and lowering lever is fulcrumed. Another object is to provide means on the lever for steadyng the wheel during the process of raising and lowering the same. Another 65 object is to provide a two part wheel raising and lowering lever with interlocking means whereby the two parts of the lever may be rigidly connected together as one element and whereby the one may be readily 70 disconnected from the other. Another object is to provide a carrier plate and two part lever with interlocking means between the plate and two part lever, whereby the 75 carrier plate and lever may be positively secured together, and whereby the parts may be readily disconnected from each other. Another object is to reduce to a minimum, 80 the number of parts of wheel raising and lowering devices without in any way sacrificing the efficiency thereof.

Many of the former types of metal wheels have been provided with hub-apertures, and the ordinary wheel lifting device may be used on such wheels, but in cases where 85 the hub-aperture is omitted, or is closed by an ornamental hub cap or the like, such wheel lifting devices become useless. One of the objects of the present invention is to provide a wheel raising and 90 lowering device which may be used with metal wheels unprovided with any hub-aperture, and metal wheels in which the hub-aperture is permanently closed by a hub cap or other ornamental center piece. 95

With these and other objects and advantages in view, this invention consists in the several novel features of construction and arrangement of parts, a description of which, will be clearly set forth in the following specification and the essential features of which will be more particularly defined in the appended claims. 100

The invention is clearly illustrated in the

drawings accompanying this specification in which:

Fig. 1 is a central, vertical cross-section taken through a wheel raising and lowering device embodying one form of the present invention with the wheel bolts removed and the lever in position for lowering the wheel, the lever and wheel being shown in dotted lines, in lowered position; Fig. 2 is a front elevation of the carrier plate and one member of the wheel raising and lowering lever; Fig. 3 is a diagrammatic view, illustrating several positions taken by the handle or detachable portion of the lever; Fig. 4 is a view similar to Fig. 1 but showing the lever and wheel in a different position from that shown in Fig. 1; Fig. 5 is a detail, front elevation of the fragment of the carrier plate; Fig. 6 is a detail, front elevation of a fragment of the fixed part of the lever; Fig. 7 is a perspective view of a fragment of the handle or detachable part of the lever; Fig. 8 is a horizontal cross-section taken on the line 8—8 of Fig. 2; Fig. 9 is a central, vertical section through a modified form of the invention; Fig. 10 is a front elevation of the carrier plate and fixed member of the lever shown in Fig. 9; Fig. 11 is a detail, vertical cross-section taken on the line 11—11 of Fig. 10, but showing fragments of the handle or detachable portion of the lever and wheel in connection therewith; Fig. 12 is a detail, horizontal section taken on the line 12—12 of Fig. 11; Fig. 13 is a detail elevation of a fragment of the fixed portion of the lever seen in Fig. 11; Fig. 14 is a detail rear elevation of the carrier parts seen in Fig. 11; Fig. 15 is a perspective view of a fragment of the handle or detachable part of the lever seen in Fig. 11; Fig. 16 is a diagrammatic view, illustrating the several positions taken by the handle portion of the lever seen in Fig. 11 when being applied to the fixed portion of the lever; Fig. 17 is a detail, central vertical section showing the application of a lock to the carrier plate and wheel; Fig. 18 is a rear elevation thereof looking in the direction of the arrow 18 in Fig. 17; Fig. 19 is a side elevation of a fragment of a motor vehicle showing the application of the invention to a carrier bracket employed at the side of the vehicle; Fig. 20 is a front elevation of the carrier plate and fixed lever employed in the construction shown in Fig. 19; Fig. 21 is a vertical section taken on the line 21—21 of Fig. 20; Fig. 22 is a fragmental, vertical section illustrating an additional improvement for releasing the wheel from the carrier plate, and Fig. 23 is a view similar to Fig. 22 but showing the parts in a different position.

Referring to said drawings, and first to Figs. 1 to 8 inclusive, the reference character 25 designates a spare wheel carrier

plate, which is secured to and supported by bracket arms 26. The arms 26 extend to some convenient part of the automobile frame or body, and are rigidly secured thereto. In the form of the invention illustrated, the carrier plate 25 is substantially circular in form and is constructed of sheet metal, struck up with suitable dies to provide two horizontal channel sections, or ribs 27. The channel sections or ribs 27 are formed with depressed portions 28 to provide spaces for receiving one member 29 of the wheel raising and lowering lever A. Internally threaded socket members 30 are secured to the channel portions 27 of the carrier plate and extend to the bracket arms 26, where they are formed with threaded stems 31 that extend through the bracket arms, and have nuts on their outer ends that fasten the socket members 30, and therewith the carrier plate 25, to the bracket arms 26.

The lower portion of the carrier plate is struck up to provide two ears 32, between which the member 29 of the lever A is held, and a pivot pin, or pintle, 33 is passed through said ears and through the lever member 29 and pivotally connects said lever to the carrier plate. The lever is free to swing from the position shown in full lines in Fig. 1, to that shown in dotted lines in Fig. 1. The wheel raising and lowering lever A, comprises two members, namely the member 29, and a member 34 which is detachably connected to the lever member 29, and said lever members have interlocking connections between them, whereby the two may be positively connected together so as to operate as one element, and whereby they may be disconnected from each other when not in use. The carrier plate and detachable lever member are also provided with interlocking connections, whereby the lever may be temporarily locked to said carrier plate, as for instance, whenever a spare wheel is being bolted to the carrier plate, or unbolted therefrom. The lever is also provided with a part 34^b arranged to be inserted through a hole, as for instance, any one of the bolt holes "b" with which the metal vehicle wheels B, are usually provided, and said part 34^b of the lever is so arranged that the lever may be readily connected to a wheel when needed to raise it from the ground and place it upon the carrier plate, and to lower it to the ground. That feature of the invention which concerns the lever will now be described in detail.

In the upper end portion of the lever member 29, is a keyhole slot 35 (see Fig. 6) and the detachable lever member 34 is formed at the end, which engages with the lever member 29, with a stem 36 (see Fig. 7) which is arranged to be inserted through said keyhole slot 35. At the stem portion 36, the lever member 34 is formed with a shoul-

der 37, which is arranged to abut against the outer face of the lever member 29 when the stem 36 has been inserted through the key-hole slot 35, and the stem is formed with a laterally projecting lug 38 which is arranged to pass through the notch portion 35^a of the keyhole slot 35 when inserting the stem therethrough. Said lug 38 is arranged to engage behind the lever member 29 whenever the lug 38 is moved out of alignment with the notch 35^a of the keyhole slot 35, thereby locking the lever part 29 to the part 34 between the shoulder 37 and lug 38.

The plate 25 has a keyhole slot 39 in its upper end with which the keyhole slot 35 of the lever part 29 is arranged to register when the lever part 29 is in upright position. Said keyhole slot 39 has notches 39^a, 39^b, 39^c, and the notch 39^a registers with the notch 35^a of the keyhole slot 35, whenever the lever member 29 is in its raised position, whereby the stem 36 may be inserted through both key-hole slots 35 and 39. The stem has a second lug 40, which is arranged in alignment with the lug 38, and said lug 40 passes through the notch 39^a of the keyhole slot 39 in the carrier plate, whenever the stem 36 of the lever member 34 is inserted through the key-hole slots. In Fig. 3 is shown diagrammatically at A, the position in which the lever member 34 is held when inserting the stem 36 thereof through the keyhole slots 35 and 39, at B is shown the position occupied by the lever member 34 when temporarily locking the lever to the carrier plate, and at C a point where the lever member 34 is locked to the lever member 29 and unlocked from the plate 25. The lug 40 locks the lever A to the plate 25 whenever the lug is moved out of alignment with the notches 39^a, 39^b.

For convenience in connecting the lever with the wheel, or disconnecting it therefrom, the lever member 34 is formed of two sections 34^a and 34^b which are detachably connected together by any suitable means. In the form shown, the section or part 34^a has a socket member 34^c secured upon one end, which is arranged to slip over the end of the section or part 34^b, and the part 34^b has a pin 34^e which enters a notch 34^d in the socket member 34^c of the lever member 34.

It is well understood that the metal wheels are provided with the usual bolt holes b, through which bolts or studs are passed to fasten them to the vehicle hubs, and in the form illustrated in Figs. 1 to 8 the usual hub-aperture of the wheel is permanently closed by a hub cap plate b¹. The part 34^b of lever member 34 is of less diameter than the bolt holes b whereby it may be readily passed through any one of them, and said part 34^b is bent into an arc of a circle, between its ends, in order that when the lever member 34 is interlocked with the lever member 25, in position to lower the wheel

from the carrier plate, the handle portion, or part 34^a, of the lever may extend in an upright, or generally upright, position as is clearly indicated in Fig. 1, and in order that the wheel may be suspended freely when being lowered to the ground. The upper end, or free end, of the lever member 29 is forked as at 41, and the ends of the forks are arranged to engage the inner face of the metal wheel and hold it from wobbling when being lowered to the ground or raised therefrom to the carrier plate.

The carrier plate, is shown as provided with four bolt holes and the keyhole slot 39. These holes and slots are spaced equidistant, and register with the bolt holes of the wheel when the latter is placed upon the carrier plate. The bolts 42 are screwed into the internally threaded socket members 30.

To demount a wheel from the carrier plate, the stem 36 of the lever member 34 is inserted through the bolt hole of the wheel which registers with the keyhole slots, and turned on the axis of the stem 36 until the lugs 38, 40 are out of register with the slots 35^a, 39^a; the lugs 38 and 40 thereupon, lock the lever members together and to the carrier plate. The bolts 42 are unscrewed and the lever member or handle 34^a swung upward into the position seen in full lines in Fig. 1. In this position the lug 40 registers with the notch 39^b of the keyhole slot 39 of the carrier plate, and is free to be drawn forward through said keyhole slot. The lever A is swung downward, thereby lowering the wheel to the ground.

It will be observed that while the wheel is being lowered it is suspended by the curved portion 34^b of the lever member 34 and that the forks 41 of the lever engage the rear face of the wheel thereby steadyng it and preventing it from wobbling while being lowered. After the wheel has been lowered to the ground the handle portion 34^a is detached from the part 34^b and the wheel slipped off the part 34^b.

To raise a wheel to the carrier plate, the wheel is stood up in the front of the lever members 29 and 34^b and the latter member is inserted through a bolt hole b, of the wheel. The handle portion 34^a is slipped upon the part 34^b, and the lever A is swung upward until the stem 36 enters the keyhole slot 39 of the carrier plate, whereupon the lever member 34^a is permitted to swing down upon the axis of the stem 36, to temporarily lock the lever to the carrier plate, after which the bolts 42 are screwed in place, and the lever member 34 is swung into the position indicated at A in Fig. 3 and withdrawn from the key-hole slots of the carrier plate, and lever member 29, and bolt hole of the wheel.

In Figs. 9 to 16 inclusive, a modified form of the invention is illustrated, and in this form, the general construction of the carrier plate is the same as that illustrated in

the preferred form. The lever member 29¹ is formed of sheet metal, and has ears 29² struck up therefrom that embrace the ears 32² of the carrier plate. A hinge pin or 5 pindle 33¹ connects the lever member 29¹ with the carrier plate 25¹. This form of the invention may be used in connection with wheels that are fornied with hub-apertures, and in such cases the lever member 10 29¹ is formed with a struck up portion 29³ which is generally circular in form, and which enters and fits in the hub-aperture of the wheel, when the latter is secured in place upon the carrier plate. This arrangement 15 gives a neat and pleasing, finished appearance to the parts and dispenses with the need of any additional cover plate over the hub-aperture. The handle or lever member 34¹ comprises a single piece, and it has 20 interlocking connections with the lever member 29¹ and carrier plate 25¹, which are slightly different from those embodied in the preferred form. In this case a notch 35¹ is provided in the end of the lever member 29¹ through which the stem 36¹ of the lever member 34¹ extends. The slot 39¹ of 25 the carrier plate instead of having notches, as in the preferred form, has an enlarged opening at one side and the top as at 39², through which the lug 40¹ may be withdrawn when the lever member 34¹ is held in 30 upright position. The stem 36¹ is formed with lugs 38¹ that co-act with the shoulder 37¹ on the stem, to lock the lever member 35 29¹ therebetween. In this form of lever arrangement, the handle portion 34¹ is placed at right angles to the lever member 29¹, namely in the position indicated at A 40 in Fig. 16 when inserting the stem into the bolt hole of the wheel, the notch 35¹ and the keyhole slot 39¹. It is locked to the lever member 29¹ by swinging it downward or swinging it upward as in the preferred form. When the lever is lowered, the handle 45 portion is disconnectible from the part 29¹ by drawing the stem out through the open end of the notch 35¹. The bottom 35^x of the notch 35¹ is flat and one 38° end of one lug 38¹ is made flat to correspond therewith, whereby the stem 36¹ may be inserted by 50 passing the flat end of the lug 38¹ along the flat bottom of the notch. The two parts of the lever are locked together when the lever part 34¹ is turned at any other angle. 55 In the form of the invention just described, it is found desirable to build out the carrier plate at the sides of the lever portion 29¹ in order that the wheel may bear against the plate. The material itself 60 may be forced outward, or it may be built up by pieces 25^s of substantially the same thickness as the thickness of the metal of the lever part 29¹. These pieces 25^s may 65 be secured to the plate in any suitable manner.

In Figs. 17 and 18 is shown a lock device for locking the wheel to the carrier plate. The same comprises a bolt 45 arranged to extend through the bolt hole of the wheel, through the notch or slot in the fixed lever member and through the keyhole slot of the carrier plate. This bolt is provided with lugs 45^a, 45^b for engaging in the notch 39² and behind the carrier plate. On the forward end of the bolt may be placed a 70 washer 46 which bears against the outer edge of the bolt hole and a padlock 47 may be secured in a hole in the outer end portion of the bolt. This simple arrangement 75 effectively guards against unauthorized persons removing the wheel from the carrier plate.

In the form illustrated in Figs. 19 to 21, inclusive, the device is shown as attached to the side of a motor vehicle and in general 80 may be constructed like either of the forms illustrated. In cases where the fender 48 or running board is provided with a pocket 49 for receiving the tire of the spare wheel, it is necessary to lift the spare wheel out of 85 the pocket before it can be lowered to the ground. The lever member 29^x in this case has a laterally bent portion 29° which terminates above the bolt hole 30^x of the carrier plate 25^x and the upper end of the carrier plate is extended upward and its keyhole slot is placed behind the keyhole slot 90 of the lever member. To lower a wheel from the carrier plate all of the bolts except the one b^x in the bolt hole 30^x are 95 unscrewed, the latter one is backed off somewhat, and the wheel is swung upward upon the bolt b^x in the hole 30^x as a fulcrum until another bolt hole comes to register with the slots in lever member 29^x and carrier 25^x. 100 The upper handle member 34^x is then inserted in the manner heretofore described, bolt b^x removed and the wheel lowered and disconnected in the same manner. The 105 wheel is replaced by reversing the order of procedure just described. The wheel may be locked in place by locking means as shown in Figs. 17 and 18. In this case the lever 29^x has a key hole slot 45^c for the lock bolt 45 which registers with the lowermost bolt hole of the wheel. 110

Figs. 22 and 23 show an additional improvement, intended for use in cases where the spare wheel is secured upon studs that project out from the carrier plate and are arranged to extend through the bolt holes of the wheel. The lever member 34^x has a stem portion 36^x, which enters the key hole slots of the lever part 29 and plate 25 and an eccentric portion 36^y which enters a bolt 115 hole of the wheel, and acts to lift the wheel bodily when the lever member 34^x is swung upward on the axis of the stem, when the latter has been inserted into the key hole slots. This raises the wheel sufficiently to 120

clear the studs, so that when it is being swung downward, the walls of the bolt holes will pass over the projecting studs.

I claim as new and desire to secure by 5 Letters Patent:

1. A wheel raising and lowering device for de-mountable wheels, comprising a carrier plate and a two part lever fulcrumed thereon and having a wheel supporting member arranged to extend through a hole in the wheel, which is non-concentric with respect to the axis of the wheel, said two parts of the lever having interlocking connections therebetween.
2. A wheel raising and lowering device for de-mountable wheels, comprising a carrier plate and a lever, said lever comprising a member fulcrumed on the carrier plate, and a handle member connectible with, and dis-connectible from said fulcrumed member, and having a wheel supporting part arranged to extend through a hole in the wheel which is non-concentric with respect to the axis of the wheel.
3. A wheel raising and lowering device for de-mountable wheels, comprising a carrier plate and a two part lever fulcrumed thereon and having an arcuate wheel supporting member arranged to extend through a hole in the wheel, which is non-concentric with respect to the axis of the wheel, said two parts of the lever having interlocking connections therebetween.
4. A wheel raising and lowering device for de-mountable wheels, comprising a carrier plate and a two part lever fulcrumed thereon and having an arcuate wheel supporting member arranged to extend through a hole in the wheel, which is non-concentric with respect to the axis of the wheel, said two parts of the lever having interlocking connections therebetween and one part constituting a jointed handle portion.
5. A wheel raising and lowering device for de-mountable wheels, comprising a carrier plate and a two part lever fulcrumed thereon and having a wheel supporting member arranged to extend through a hole in the wheel, which is non-concentric with respect to the axis of the wheel, one member of the lever having a keyhole slot formed therein, and the other member of the lever having a stem insertable through said hole in the wheel and through said keyhole slot, and having lugs adapted to engage on both sides of said keyhole slotted lever member to lock the lever members together.
6. A wheel raising and lowering device for de-mountable wheels, comprising a carrier plate and a two part lever fulcrumed thereon and having a wheel supporting member arranged to extend through a hole in the wheel, which is non-concentric with respect to the axis of the wheel, said carrier

plate and two parts of the lever having interlocking connections therebetween.

7. A wheel raising and lowering device for de-mountable wheels, comprising a carrier plate and a two part lever fulcrumed thereon, said carrier plate and one member of said lever having keyhole slots arranged to register with each other in one position of said lever member, and the other lever member having a stem formed with lugs insertable through said keyhole slots and arranged to engage the carrier plate and slotted lever member to lock the lever and carrier plate together.

8. A wheel raising and lowering device for de-mountable wheels, comprising a carrier plate and a two part lever fulcrumed thereon, and having a wheel supporting member arranged to extend through a hole in the wheel, which is non-concentric with respect to the axis of the wheel, said two parts of the lever having interlocking connections therebetween, and one being formed with a circular raised portion adapted to fit in the hub-aperture of a wheel.

9. A wheel raising and lowering device for de-mountable wheels, comprising a carrier plate and a two part lever fulcrumed thereon and having an arcuate wheel supporting member arranged to extend through a hole in the wheel, which is non-concentric with respect to the axis of the wheel, said two parts of the lever having interlocking connections therebetween, and the fulcrumed lever member having a wheel steady-ing element above its connection with the other member.

10. A wheel raising and lowering device for de-mountable wheels, comprising a carrier plate and a two part lever fulcrumed thereon and having an arcuate wheel supporting member arranged to extend through a hole in the wheel which is non-concentric with respect to the axis of the wheel, said two parts of the lever having interlocking connections therebetween, and the fulcrumed lever member having a fork above its connection with the other member, arranged to engage the side of the wheel to steady the same while being raised or lowered.

11. In a wheel raising and lowering device, a sheet metal carrier plate formed with two parallel, horizontal channel shaped sections, said channel sections having depressed portions between their ends, and a lever fulcrumed on said carrier plate and arranged in one position to stand in said depressions of said channel sections.

12. A wheel raising and lowering device, comprising a carrier plate having bolt holes circumferentially arranged therein, and a two part lever fulcrumed to said plate and having a wheel supporting member arranged

to extend through a hole in the wheel, which is non-concentric with the axis of the wheel, said wheel support being disposed laterally of the median line of the carrier plate, and a removable fulcrum element pivotally connecting the wheel with the carrier plate, whereby said wheel may be swung upward on said fulcrum element to bring one of its non-concentric holes into register with said wheel support.

13. In a wheel raising and lowering device a carrier plate, and a two part lever fulcrumed thereon and one part having an arcuate wheel supporting element arranged 15 to extend through the wheel, the other part of said lever having a wheel steadyng element arranged to engage the rear face of the wheel and steady the same on the arcuate supporting element while supported by the 20 lever.

14. In a wheel raising and lowering device a carrier plate having an aperture therein, and having wheel supports, a two part lever fulcrumed on said carrier plate, 25 one of said lever parts having a stem portion arranged to swivel in said aperture in the carrier plate and having an eccentric part entering a hole in the wheel, whereby the wheel may be raised from the supports 30 on the carrier plate to disengage it therefrom.

15. A wheel raising and lowering device

for demountable wheels, comprising a carrier plate, and a wheel raising and lowering lever fulcrumed thereon, said lever having a detachable handle portion provided with a wheel sustaining element.

16. A wheel raising and lowering device for demountable wheels, comprising a carrier plate, arranged to support a wheel, a 40 lever member fulcrumed to said plate, and disposed at the rear of said wheel, and a handle member for said lever, connected with said first mentioned lever member through a hole in said wheel, said handle member having a wheel sustaining element located in front of said first mentioned lever member, whereby said handle member may sustain the wheel when raising and lowering the same.

17. A wheel raising and lowering device for demountable wheels, comprising a carrier plate and a wheel raising and lowering lever fulcrumed thereto and having three points of contact with a wheel raised or lowered thereby, one of said points of contact comprising an arcuate element extending through a hole in the wheel, and arranged to sustain the wheel while being raised or lowered, and the other two points of contact comprising elements engaging the rear face of the wheel to steady the same on said sustaining element.

LEWIS E. FAGAN.
